UNITED STATES PATENT OFFICE

NORMAN L. SNOW AND SAMUEL F. COX, OF DETROIT, MICHIGAN, ASSIGNEES TO DIAMOND POWER SPECIALTY CORPORATION, OF DETROIT, MICHIGAN, A CORPORATION OF MICHIGAN

BOILER CLEANER

Application filed June 28, 1926. Serial No. 119,192.

This invention relates to boiler cleaners and refers more particularly to a boiler cleaner employing the discharge of steam or other cleaning fluid to dislodge soot and other deposits from the tubes and other parts of a boiler to be cleaned.

One of the objects of the invention resides in providing a boiler cleaner having an improved means for controlling the supply of cleaning fluid to the element. A further feature of the invention resides in the provision of a removable and replaceable cam element, whereby the admission of cleaning fluid, with respect to angular positions of the blower element may be readily varied. A still further feature of the invention resides in the provision of a rotatable blower element, which in one form may be rotated throughout a plurality of revolutions with the valve preferably automatically seating at the completion of each revolution. In a modified form, the invention provides a rotatable blower element which is adapted to be oscillated with the valve preferably automatically seating at the end of the rotative movement in each direction.

Referring to the accompanying drawings in which like reference characters indicate corresponding parts,

Figure 1 is a sectional elevation view of our invention,

Figure 2 is an end elevation view of the cam and valve with the cover plate removed showing the valve in closed position,

Figure 3 is a like view showing the valve in open position,

Figure 4 is an elevation view corresponding to Figure 2, illustrating a modified construction in which the blower element oscillates, and

Figure 5 is an elevation view of the form shown in Figure 4 and corresponding to the valve position shown in Figure 3.

In the drawings reference character 10 illustrates the boiler wall and 11 the usual boiler tubes. To clean the tubes and other parts of the boiler, we have provided the soot blower element 12, fitted as usual with cleaning fluid discharge nozzles 13. The element

12 extends through wall box 14 and is journaled in the head A.

For imparting rotation to the blower element, we may provide sheave wheel 15 mounted on shaft 16, positioned in bracket 17 forming part of the head A. Keyed to one end of shaft 16 as at 18 is a driving pinion 19 meshing with a driven gear 20, which in turn is fixed as by set screw 21 to the element. One end of the element passes into the head A through gland 22 and packing 23 and threadedly carries a valve cage 24, the latter being provided with a suitable cleaning fluid port or valve seat 25. Cleaning fluid may be admitted to the interior of head A, in any suitable manner, as by supply pipe 26.

Pivots attached to valve cage 24, and adapted to rotate therewith, upon rotation of the blower element, is the valve 27 pivoted on pin 28. This valve may be of the plate type, as shown, and is opened or closed by swinging upon pin 28. To govern this swinging movement of the valve, relative to the valve port 25, we have provided an extension 27^a of the plate valve with a pin 28^a carrying roller 29. This roller runs in a machined guide-way 30, of the stationary cam element 31, the latter being secured to the head cover plate 32 by counter-sunk screws 33. The cover plate 32 may be attached to head A by bolts 34 and serves to close the open end of the head.

In Figure 2 the plate valve 27 is shown in its closed position, while in Figure 3, the valve is shown unseated with respect to the port or valve seat 25. The guide-way 30 is made to vary with the degree of blowing arc desired. Thus it may be formed with a high level 35 and a low level 36. When roller 29 runs from the low level 36 to the high level 35, as shown in Figure 2, valve 27 swings on its pivot 28 moving against the limiting stop pin 37 and covering port 25. Continued clock-wise rotation of the blower element (as seen in Figure 2) carrying with it valve cage 24, and the plate valve 27, causes the roller 29 to progress along the high level portion 35 until it reaches the point 40 which is the transition point from the high to the low level. At this point the valve 27 is swung

about its pivot 28 over against the other limiting stop pin 39 and uncovering the port 25 as seen in Figure 3. The valve is held open throughout the low level of the guide-way 5 over the arc designated in Figure 3. Upon the roller reaching point 38, it again passes to the high level portion 35 restoring the valve 27 to its position shown in Figure 2, closing port 25.

10 When different arcs of blowing are desired with our invention, the cam element 31 including guide-way 30 may be readily removed and replaced by another element having the desired guide-way, by simply removing the cover plate 32 and counter-sunk screws 33, the cover plate and cam element being conveniently removable as a unit.

In Figures 2 and 3, the blower element may be continuously rotated in one direction, 20 the valve automatically seating, at the completion of the blowing arc and unseating at the beginning of the blowing arc for each rotation of the blower element. If desired the operator might impart an oscillatory motion to the blower element, whereby the valve 25 will automatically seat at the completion of the rotation in each direction.

In order that the operator might be advised when the valve is seated when an oscillatory movement is imparted to the blower element, we have provided stops 41 and 42, as shown in Figures 4 and 5. These stops are located in the guide-way 30 and are engageable by roller 29, when the latter moves from 30 the low level 36 to the high level 35 for each direction of rotation of the blower element.

What we claim as our invention is:

1. The combination with a rotatable blower element, of a valve controlling the admission 40 of cleaning fluid thereto, said valve being rotatable in unison with the blower element and also transversely movable relative thereto, and means responsive to rotation of the blower element for maintaining said valve unseated through a predetermined blowing arc and seating said valve at both ends of said blowing arc.

2. The combination with a rotatable blower element adapted to be oscillated between predetermined points, the arc of oscillation including the blowing arc, of a valve controlling the admission of cleaning fluid thereto, said valve being rotatable in unison with the blower element and also transversely movable relative thereto, and means responsive to oscillation of the blower element between said predetermined points for maintaining said valve unseated when the blower element is 50 moving through said blowing arc and seating said valve at both ends of said blowing arc.

3. The combination with a rotatable blower element adapted for unlimited rotation in a given direction, of a valve controlling the admission of cleaning fluid thereto, said valve

being rotatable in unison with the blower element and also transversely movable relative thereto, and means responsive to a continuous rotative movement of the blower element for maintaining said valve unseated throughout a predetermined arc of each revolution of the blower element and for maintaining said valve seated throughout substantially the remainder of each revolution of the blower element.

4. The combination with a rotatable blower element adapted to be oscillated between predetermined points, the arc of oscillation including the blowing arc, of a valve controlling the admission of cleaning fluid thereto, 80 said valve being rotatable in unison with the blower element and also transversely movable relative thereto, said blower element being provided with a seat for said valve, and means responsive to oscillation of the blower element between said predetermined points for maintaining said valve unseated when the blower element is moving through said blowing arc and seating said valve at both ends of said blowing arc.

5. The combination with a rotatable blower element adapted for unlimited rotation in a given direction, of a valve controlling the admission of cleaning fluid thereto, said valve being rotatable in unison with the blower element and also transversely movable relative thereto, said blower element being provided with a seat for said valve, and means responsive to a continuous rotative movement of the blower element for maintaining said valve unseated throughout a predetermined arc of each revolution of the blower element and for maintaining said valve seated throughout substantially the remainder of each revolution of the blower element.

6. The combination with a rotary blower element and means for rotating the same, of a valve for controlling the admission of cleaning fluid to the blower element, means for pivotally mounting said valve upon said blower element, said valve being thus rotatable with the blower element and also movable on its pivot relative to said blower element, and means responsive to rotation of the blower element for maintaining said valve unseated through predetermined blowing arc and seating said valve at both ends of said blowing arc.

7. The combination with a rotary blower element and means for rotating the same, of a valve cage rotatable with the element and provided with a port for admitting cleaning fluid to said blower element, a plate valve, means pivotally supporting said valve on the valve cage so as to seat on said port, a cam provided with a guide-way, a pin carried by the valve extending substantially perpendicularly from the face of said valve, a roller engageable in said guide-way and carried by the

pin, said guide-way being shaped to maintain said valve unseated, upon rotation of the blower element, through a predetermined blowing arc and to seat said valve at both 5 ends of said blowing arc.

5 In testimony whereof we affix our signatures.
